LENS FOR SKI GOGGLES OR THE LIKE

George R. Rabuse, Sunfish Lake, Minn., assignor to Minnesota Mining and Manufacturing Company, St. Paul, Minn.

Filed Feb. 12, 1973, Ser. No. 331,537

Term of patent 14 years

Int. Cl. D2—03

U.S. Cl. D2—234

FIG. 1

FIG. 2

FIG. 3

FIG. 4

FIG. 1 is a top plan view of a lens, for ski goggles or the like showing my new design;

FIG. 2 is a front elevational view thereof;

FIG. 3 is a bottom plan view thereof; and

FIG. 4 is a side view thereof.

The lens is shaded to indicate contrast.

I claim:

The ornamental design for a lens for ski goggles or the like, substantially as shown and described.
